UNITED STATES PATENT OFFICE

GEORGE A. SPENCER, OF TIPTON, INDIANA, ASSIGNOR TO THE OAKES MANUFACTURING CO., OF TIPTON, INDIANA, A CORPORATION OF INDIANA

STORAGE BROODER

Application filed July 2, 1929. Serial No. 375,495.

This invention relates to poultry brooders and an object of the invention is to provide an improved brooder in which large numbers of chicks may be brooded economically and in a limited amount of floor space.

A further object is to provide a brooder with compartments of the same or different temperatures so arranged that the chicks may select that part of the compartment having 10 the temperature best suited to them.

The invention further consists of improved means for heating the brooder and for ventilating the same.

A further object is to provide a brooder 15 which may be easily kept clean and sanitary.

Further objects and advantages will become apparent as the description proceeds.

Referring to the accompanying drawings, which are made a part hereof and on which 20 similar reference characters indicate similar parts,

Figure 1 is a perspective of the brooder,

Figure 2 is a front view with parts shown in section,

25 Figure 3 is a partial plan view with parts broken away to show the air circulating means, and

Figure 4 is a section on line 4—4 of Figure 2.

30 In the drawings numeral 10 indicates the legs upon which the structure is supported, these legs forming in connection with horizontal bars 11 a framework upon which is built a number of compartments and sections 35 of the brooder. The brooder may be, and preferably is, composed of a number of superposed tiers, each tier being divided into a number of compartments by means of partition walls 12. The ends 13 of the tiers are closed 40 by any suitable wall material such as celoglass or some similar material. The outer ends of the compartments are provided with downwardly opening doors 14. The floor of each compartment consists of a screen plate 15 of

45 any suitable material, the plates being removably positioned in the compartment and having their sides preferably resting upon the cross bars 11 which form a part of the framework of the brooder. Positioned beneath the 50 floor screens 15 are dropping pans 16. The

pans 16 rest on portions of the cross frame 11 and may readily be taken out to be cleaned. The inner ends of the compartments are closed by downwardly opening doors 17. These doors do not have a tight fit with the compartment but instead have openings through which heated air may pass into the compartments. The compartments are all divided by means of transverse curtains 18. The curtains divide the compartment into a chamber 19 having a relatively high temperature and a chamber 20 having a temperature slightly less than that in the brooder chamber 19 and which decreases as the outer end of the chamber is approached.

55 In providing this structure dependence is placed upon the instinctive movement of chicks of all ages toward the space which is of the temperature particularly suited to the age needs of the chick.

60 The tiers of compartments have a closed chamber 21 between them into which chamber heated air is driven and from which chamber the air enters into the several brooding compartments.

65 Mounted on top of the compartments is a chamber 22 having heating units 23 therein, these heating units being of any convenient sort. Here they are shown as a series of pipes through which any heating fluid medium such as steam, hot water or air may be circulated for heating the air in the chamber. The flow of heating fluid through the conduits may be controlled by means of a valve 24. The top of the heating chamber 85 is provided with a pair of inlet openings 25. These openings may be adjustable by means of slides 26. A fan 27 is positioned above an opening 28 in the lower floor of the heating chamber for circulating air through 90 the chamber and delivering it into the compartment 21.

95 In operation fresh air is drawn by the fan 27 through the inlet ports 25 around the heating coils 23 and through the opening 28 into the chamber 21. The air in this chamber is slightly above atmospheric pressure and is driven through the doors 17 into the compartment 19. This latter compartment will be maintained at a relatively high tem- 100

perature, say for example something above 98 degrees. The flexible partition 18 will maintain the temperature in this chamber at the desired high degree. Warm air will, however, pass through and around the flexible partition 18 into the chamber 20. This chamber is open so that the temperature at the inner end is only slightly below that in the brooder chamber 19, but tends downward toward the outer end approaching the temperature of the room in which the brooder is placed. The chamber 20 is preferably the feeding chamber for the chicks. Since the chicks may pass freely from one chamber to another they will instinctively collect in the chamber and in the portions of the chamber best suited to their needs, i. e. the younger chicks will tend to collect and remain in the warm chambers 19, whereas the older chickens will collect in the chambers 20 since these older chicks do not require temperature as high as the younger ones. It will therefore be seen that my brooder is suited for chicks of any age without any changes of the structure or any change in the heating medium, since the chickens may find the temperature that suits their needs and collect there. The plurality of tiers enables me to conserve space and thus care for a large number of chickens in a room having relatively small floor space. All parts of the brooder compartments are readily accessible to be cleaned.

It will be obvious to those skilled in the art that various changes may be made in my device without departing from the spirit of my invention, and therefore I do not limit myself to what is shown in the drawings and described in the specification, but only as set forth in the appended claim.

Having thus fully described my said invention, what I claim as new and desire to secure by Letters Patent, is:

A storage brooder comprising groups of superposed tiers divided into a plurality of sections, each section being provided with a flexible transverse partition dividing it into inner and outer compartments, a central chamber located between said groups of tiers, the sides and top of said chamber completely enclosing the sides and tops of said inner compartments and further forming a heating chamber above said groups of tiers, a wire cloth floor removably positioned in each section, a removable metal tray secured beneath said floor, a heating unit mounted in said heating chamber, and means for circulating and forcing the warmed air through said brooder, substantially as set forth.

In witness whereof, I have hereunto set my hand at Washington, D. C. this first day of July, A. D. nineteen hundred and twenty-nine.

GEORGE A. SPENCER.
